UNITED STATES PATENT OFFICE.

FINLAY R. MCQUEEN, OF MINNEAPOLIS, MINNESOTA.

CONTROLLING DEVICE FOR ELEVATOR-BIN SLIDES.

No. 923,291.

Specification of Letters Patent.

Patented June 1, 1909.

Application filed January 11, 1908. Serial No. 410,368.

To all whom it may concern:

Be it known that I, FINLAY R. MCQUEEN, of Minneapolis, Hennepin county, Minnesota, have invented certain new and useful Improvements in Controlling Devices for Elevator-Bin Slides, of which the following is a specification.

In the operation of a grain elevator, bins of large capacity are employed into which the grain from cars standing on the tracks, is discharged. This grain is then allowed to flow from the bins on to a carrier belt which conveys it to the elevator leg. The bins are provided with slides covering discharge openings and as the grain in the bins often includes several different grades it is important that the flow from one bin be stopped before the discharge begins from another bin in order to avoid mixing of the different grades. A device for the same purpose is shown and described in my pending application No. 410,369, filed Jan. 11, 1908.

The object of my invention therefore, is to provide an apparatus whereby the slides of each bin are positively controlled and no two bins can be opened to discharge their contents at the same time, and it will be impossible to open one bin without closing all the others.

My invention consists generally in various constructions and combinations, all as herein-after described and particularly pointed out in the claims.

In the accompanying drawings, forming part of this specification, Figure 1 is an elevation of a bin-slide-controlling apparatus embodying my invention. Fig. 2 is a plan view of the same. Fig. 3 is a detail side view of the levers attached to the slides and the mechanism for controlling the same. Fig. 4 is an edge view of the levers with the connections at their lower ends omitted. Fig. 5 is a plan section on the line *e*—*e* of Fig. 3. Fig. 6 is a plan view illustrating the mechanism for locking the levers in a closed position. Fig. 7 is a detail view of the wheels by means of which the movement of the levers is controlled. Figs. 8, 9, 10 and 11 are sectional views taken respectively on the section lines *a*—*a*, *b*—*b*, *c*—*c* and *d*—*d* of Fig. 7.

In the drawing, 2 represents the bins from which the grain is discharged upon the carrier belt (not shown). These bins have discharge openings in their bottoms normally covered by slides 3. These slides are connected at 4 to horizontally arranged oper-

ating rods 5, 6, 7 and 8, arranged parallel with one another and operating between suitable guide wheels 9. The reciprocation of these rods will operate the slides to open and close them and each rod is connected to an oscillating bar 10 that is pivoted at a point intermediate to its ends in a bracket 11, the bars oscillating in vertical planes and having their upper ends connected by rods 12 to a series of levers 13, 14, 15 and 16. The rods 12 are provided with turn buckles 17 by means of which the proper adjustment to obtain the desired throw of the levers is obtained.

The levers are pivoted at points intermediate to their ends and a series of wheels 18, 19, 20 and 21 are provided near said levers and have their peripheries in contact therewith and normally locking said levers in an inclined position and positively preventing the slides from being opened. The wheels are mounted on a shaft 22 that has bearings 23 on a base 24 and carries a beveled gear 25 meshing with a similar gear 26 on the lower end of a post 27. The upper end of said post is provided with a hand wheel 28. Upon turning this post the wheels will be revolved. Each wheel is provided with a flattened surface 29 arranged at a different point on the periphery from that of each of the other wheels, for instance, the flat surface of the first wheel may be arranged on the first quarter, that of the second wheel on the second quarter, the third wheel on the third quarter and the fourth wheel on the fourth quarter. The result of this arrangement is that when the flat surface is opposite the edge of the lever contiguous to said surface, said lever may be swung to a vertical position to open the slide. No two of the flat surfaces, however, will be opposite their levers at the same time and consequently when one lever is operated to open its slide all the other levers will be locked, and if the slide of one bin is open and it is desired to open the slide of another bin, then the lever of the first bin must be operated to close its slide before the lever of the second bin can be operated to open its slide.

I have shown four levers and four wheels, but obviously this number may be varied according to the number of bins to be controlled. The principle will be the same whether there are a less or greater number of levers and wheels. The wheels and the lower portions of the levers will generally be located

below the floor 30, the operating post and handle projecting above said floor, and to enable the attendant to intelligently control the movement of the slides I provide a 5 plate 31 on the floor and a disk 32 secured to the post 27 above said plate. Notches 33 and 34 are provided in the periphery of said disk and alternating with one another, and a dog 35 is mounted on the base 31 and 10 adapted to drop into said notches. The notches 34 are marked to correspond with the operating levers and when the disk 32 has been revolved and the dog allowed to drop into one of the notches 34, the attendant 15 will understand that the wheel controlling the movement of the lever having the number or mark corresponding to that on the notch, has been revolved to allow the said lever to be moved to an open position 20 and the bin slide connected with that lever actuated to open the bin and discharge the grain. The adjustment of the dog in any of the other notches 34 will produce a similar result, the attendant understanding that by 25 revolving the disk until the dog drops into one of the notches 34, that the lever marked to correspond to that notch, may then be operated. Whenever the dog is in one of the alternate notches 33 all the levers will 30 be locked and it will be impossible to operate a slide to release the grain. With this device the opening of a slide cannot take place until all the others are closed and it will be impossible for a mixture of grain of different 35 grades to occur.

I claim as my invention:

1. The combination, with two or more bins having discharge openings and slides therefor, of operating levers connected with 40 said slides and a controlling device for said levers, said device including revolving wheels having flattened areas that are adapted to contact with said levers and preventing simultaneous movement of two or more of said 45 levers but permitting successive independent movement thereof.

2. The combination, with two or more bins having discharge openings and slides therefor, and operating levers connected with 50 said slides and a revolving controlling device arranged to prevent simultaneous movement of said levers but permitting successive independent movement thereof said controlling device including wheels having flattened 55 peripheries which engage said levers.

3. The combination, with two or more bins having discharge openings and slides therefor, and a series of levers connected with said slides, of revolving wheels having 60 their peripheries in engagement with the edges of said levers, said peripheries having flattened surfaces, which when opposite the edges of said levers permit oscillation thereof, and said flattened surfaces being arranged at 65 different points on the peripheries of the

wheel whereby independent operation of each lever is permitted but simultaneous movement of two or more of them is prevented.

4. The combination, with two or more bins having discharge openings and slides therefor, and operating means for said slides, of a controlling mechanism arranged to regulate the movement of said operating means and permit independent operation of each 70 but preventing simultaneous movement of two or more of them, and an indicating mechanism connected with said controlling means whereby the attendant at a glance can determine the position of the slides said indicating mechanism having a post connected with said controlling mechanism and provided with operating means, a disk secured to said post and having peripheral notches suitably marked to represent the different 75 levers, and a dog arranged to drop into said notches, substantially as described.

5. The combination, with two or more bins having discharge openings and slides therefor, operating levers connected with 80 said slides, a series of wheels having flattened peripheries at intervals and arranged to contact with the edges of said levers, the flattened surfaces being arranged at different points on the peripheries of said wheels whereby 85 only one lever can be operated at a time, a post geared to said wheels and having a hand wheel, a disk secured to said post having a series of peripheral notches, the alternate notches being marked to correspond with the 90 different levers and a dog arranged to drop into the notches marked to correspond to the levers and indicate that the lever for that notch is free to be operated to open the slide, or to enter the notches alternating with those 95 corresponding to the levers and indicate that all the levers are in their locked position, substantially as described.

6. The combination, with two or more bins having discharge openings and slides therefor, and operating means for said slides, of a controlling mechanism arranged to regulate the movement of said operating means and permit independent operation of each 100 slide but preventing simultaneous movement of two or more of them, and an indicating mechanism connected with said controlling means and comprising a notched disk, and a dog arranged to engage said notches, and means for operating said disk to move said 105 notches past said dog.

7. The combination, with two or more bins, having discharge openings and slides therefor, of a series of operating levers arranged side by side and connected with said slides, and a controlling mechanism including 115 means arranged to be set in the path of said levers to lock them against oscillation, means for operating said locking means, and an indicating device provided in connection with 120 125 130

said operating means whereby the position of the locking means can be determined at a glance.

8. The combination, with two or more bins arranged side by side and having discharge openings and slides therefor, of a series of operating levers arranged side by side connected with said slides, wheels having flattened faces located in the path of said levers and arranged to lock them independ-

ently of one another against oscillation, and means for operating said wheels to lock or release a lever.

In witness whereof, I have hereunto set my hand this 4th day of December 1907.

FINLAY R. McQUEEN.
